DESIGN FOR THE HANDLE OF A FORK OR SPOON.

GEORGE SHARP, OF PHILADELPHIA, PENNSYLVANIA.

Design No. 2,512, dated November 27, 1866.

SPECIFICATION.

TO ALL WHOM IT MAY CONCERN:

Be it known that I, GEORGE SHARP, of the city of Philadelphia, in the State of Pennsylvania, have invented or produced a new and original ornamental Design for the Head or End of the Handle of a Ladle, Spoon, Fork, or other articles of table use, of which the following is a full, clear, and exact description, referring to the accompanying drawing making a part of this specification, and to the letters of reference marked thereon:

This invention or production relates to the shank-handles of ladles, spoons, forks, and other articles of table use which require shank-handles. It consists in making the head or end, A B, of the handle, C, in the form of a cube, having the handle attached thereto perpendicularly in the centre of one of its sides, as shown in the drawing.

What I claim as my invention, and desire to secure by Letters Patent, is—

The design for the head or end, A B, of the handle of a ladle, spoon, fork, or other articles of table use requiring shank-handles, herein set forth and shown.
